UNITED STATES PATENT OFFICE.

PHILIP A. MONTROY, OF SAN ANTONIO, TEXAS.

AUTOMATIC AUTOMOBILE-TOP.

1,280,272.

Specification of Letters Patent.

Patented Oct. 1, 1918.

Application filed June 24, 1916. Serial No. 105,652.

To all whom it may concern:

Be it known that I, PHILIP A. MONTROY, a citizen of the United States, residing at San Antonio, in the county of Bexar and 5 State of Texas, have invented certain new and useful Improvements in Automatic Automobile-Tops, of which the following is a specification.

This invention relates to vehicle tops, and 10 more particularly has for its object the provision of a vehicle top, which may be readily removed and positioned in an out of the way or inoperative manner.

The primary object of the invention re- 15 sides in the provision of a device of the character described wherein means are provided for the rolling of a curtain upon a spring actuated drum, so that when in an inoperative position the same is so arranged as to 20 constitute a neatly appearing and weather proof roll.

Another object of the invention, is to provide side curtains similarly mounted, whereby the vehicle may be readily closed upon 25 all sides, consequently protecting occupants from the elements..

The invention also contemplates the provision of means whereby the top and side curtains may be readily moved into an operative position by the occupant of the vehicle, without the necessity of leaving the same, the said means comprising a rotary drum, which is provided with the usual pawl and ratchet mechanism to prevent its 30 accidental unwinding any further, with a crank member whereby said drum may be readily rotated.

A further important characteristic of the present invention resides in the means 40 whereby the top and side curtains are supported, the said means including a pivotally supported frame member, which member may be swung from an inoperative position into an operative position through the 45 medium of a suitable connection, operated by means of a foot lever, conveniently positioned before the occupant of the car.

Other features of the invention reside in an improved manner whereby the top is rendered sufficiently rigid to allow the same to be readily adapted to be used for the purpose for which it is desired, that is, in providing the same with semi-rigid cross pieces or slats which are secured thereto by suitable 55 fastening devices.

All of the foregoing together with additional advantageous details and arrangement of parts of the preferred embodiment of my invention will be clear from the specific description hereinafter contained, when 60 read in connection with the accompanying drawings forming a part hereof, wherein said embodiments of the invention are illustrated for the purpose of facilitating full understanding of the present invention. 65

In the drawings:

Figure 1 is a side elevation of a motor vehicle showing my improved device applied;

Fig. 2 is a rear elevation, portions thereof 70 broken away and illustrating the manner in which the top and side curtains are supported;

Fig. 3 is a perspective of the frame for supporting the top and side curtains; 75

Fig. 4 is a fragmentary detail in perspective showing the construction and arrangement of the top and side curtains;

Fig. 5 is a fragmentary detail in perspective of the top, showing the flap used for securing the side curtains thereto in a folded position, and ready for rolling;

Fig. 6 is a detail in side elevation of the winding drum whereby the curtain is unrolled and moved into an operative position; and

Fig. 7 is a fragmentary view in detail showing the construction and arrangement of the foot lever for raising the pivoted supporting frame into an operative position.

Referring now to the drawings wherein like reference numerals designate like or corresponding parts throughout the several views, 1 represents a vehicle to which my improved device has been applied. Pivotally supported within the rear end of the vehicle is a supporting frame 2, the same comprising vertically disposed standards 3 and 4, which are provided with complementally arranged angularly extended arms 5 and 6, the lower end of said arms being provided with loops 7 and 8, which are adapted to receive one end of helical springs 9, while the extreme lower end thereof is provided with apertures whereby the same may be connected with cables, or cords, 10, the purpose of which shall be subsequently described.

The upper extremities of the vertical standards 3 and 4 are provided with bracket 110

UNITED STATES PATENT OFFICE.

HARRY E. MOORE, OF SMITHFIELD, NEBRASKA.

HOISTING-HOOK.

1,280,273.

Specification of Letters Patent.

Patented Oct. 1, 1918.

Original application filed December 22, 1917, Serial No. 208,413. Divided and this application filed February
